A. W. L. SCHERM'ILY.
DEVICE FOR SUSPENDING AND RELEASING SHIPS' BOATS.
APPLICATION FILED SEPT. 12, 1919.

1,402,662.

Patented Jan. 3, 1922.

INVENTOR

BY Augustus Wm Louis Schermerly
Kenneau & Forman, ATTORNEYS

UNITED STATES PATENT OFFICE.

AUGUSTUS WILLIAM LOUIS SCHERMULY, OF SUTTON, ENGLAND.

DEVICE FOR SUSPENDING AND RELEASING SHIPS' BOATS.

1,402,682.

Specification of Letters Patent.

Patented Jan. 3, 1922.

Application filed September 12, 1919. Serial No. 323,421.

(GRANTED UNDER THE PROVISIONS OF THE ACT OF MARCH 3, 1921, 41 STAT. L., 1313.)

To all whom it may concern:

Be it known that I, AUGUSTUS WILLIAM LOUIS SCHERMULY, a subject of the King of Great Britain, residing at Stonecroft, Stone 5 Cot Hill, Sutton, in the county of Surrey, England, have invented new and useful Improvements in Devices for Suspending and Releasing Ships' Boats (for which I have filed application in Great Britain on the 10 24th day of July, 1918, Patent No. 12,077,) of which the following is a specification.

My invention relates to devices for suspending and releasing ships' boats and for analogous purposes, the said devices being 15 of the kind in which the boat is suspended by the "falls" or suspending tackle (the lower ends of which are restrained from outward movement, relatively to each other, by a tie-rope) engaging with hooks at, or towards, the respective ends of the boat, one, or both, of these hooks being released from engagement with the "falls," or suspending tackle, to liberate the boat after lowering. In devices of the aforesaid kind the 20 hooks are maintained in their engaging position by pins, catches, or their equivalent, which pins, or catches, or their equivalent, are withdrawn, or otherwise manipulated, when it is required to liberate the boat.

My invention has for its object to provide improved devices of the aforesaid kind which are very simple in construction and very readily operated for attachment and detachment whilst the attachment is not liable 35 to become accidentally released, and in which the pins, catches, or their equivalent, hitherto proposed for maintaining the hooks in engagement with the "falls," or suspending tackle, are dispensed with.

I will presume, for the purposes of description only, that the devices according to my invention are to be employed for suspending ships' boats from their davits.

According to my invention the boat to be suspended is provided, towards both its bows and stern, with a hook, one or each of such hooks being a lever-hook capable of turning upon a centre and retained in securing position by the strain exerted on one side of the said centre by connected suspending devices which engage the said hooks, the said lever-hook, or each of such lever-hooks, being provided with means by which the hook can be turned into such position that the suspending device connected

with it comes towards the other side of the said centre and the strain then exerted by the said connected suspended devices will bring the lever-hook into the position in which the hooks and the suspending means 60 become disengaged from each other and release the boat, or the like.

The following is a more detailed description, with reference to the accompanying drawing, of how a device in accordance with 65 my invention can be constructed and applied, as boat-suspending and releasing gear, but I do not limit myself to the precise details of these constructions.

Figure 1 is a longitudinal section of a boat 70 showing an arrangement wherein a lever-hook is used at one end of the boat.

Figure 2 is a like view of an arrangement wherein a lever-hook is used at each end of the boat.

Referring first to Figure 1.

The part of the boat towards the fore-end is provided with a fixed hook A, somewhat inclined in an upward direction towards the bows, and the part of the boat towards its after end is provided with side-pieces, (one of which is seen at B) constituting a double standard between which is the lever-hook C, capable of turning upon a centre-pin b carried, by the said double standard, above the 80 position which the hook c of the said lever C takes when it is in its suspending and securing position so that the link of the suspending tackle, when in that position, has the part which takes the strain of the suspending tackle to one side of the centre upon which the lever-hook turns. The suspending tackle (the lower ends of which are seen at D) can be carried, in any usual, or suitable way, from the davits so that the 85 links d² of the lower blocks d of the tackle will respectively engage the hooks A and c.

The said blocks, or the links carried thereby, or other suitable parts of the tackle engaging the respective hooks, (for example, as illustrated, the rings d³ connecting the blocks and links) are connected by any suitable tie-rope, or the like, such as that shown at E, which will ensure the proper engagement of the respective hooks and 100 links when in the suspending position illustrated, the strain of the tie-rope E, or the like, tending, by its connecting the ends of the "falls," or suspending tackles, together to keep the after-link d² on the inner side of 105 110

the centre upon which the lever-hook c turns and thus retain both the after and fore hooks engaged with their respective links, until the said after-link is moved to the 5 other side of the aforesaid centre whereupon the strain of the tie-rope acts to turn the hook c in the direction to effect release of the boat.

To attach the boat for suspension, the link 10 d^2 of the forward block is passed under the fixed hook A. The lever-hook C towards the after-end of the boat is turned upwards upon its centre-pin b , and engaged with the link d^2 of the other block. Then the lever-hook 15 C is turned down between the side-pieces B of the aforesaid standard until the link d^2 of the after-block has passed the centre upon which the hook turns, that is, to the position illustrated. To release the boat the tail of 20 the lever-hook is pulled towards the stern of the boat until the link d^2 of the after-block is moved to the other side of the centre upon which the hook turns whereupon the strain of the suspending tackle will, 25 through the link d^2 of the after-block, instantly turn the lever-hook C into such a position that the hook c will slip from the link d^2 at the stern end of the boat, whilst the fore-link will slip from the inclined fixed hook A at the bows and the boat will be at 30 once released.

The lever-hook C may be provided with any suitable means for operating it for release, such as the short rope c^2 to be pulled, 35 and the standard between the side pieces of which the lever-hook is carried, may be shaped so that, when the lever-hook is in its engaging, or suspending, position, as shown in the drawing, the link d^2 of the suspending 40 tackle will be practically enclosed between the hook c and the adjacent parts of the said standard B.

The hook A, and the standard B, are shown as being connected to the boat by 45 hinge-joints, at a and b^2 , respectively; but they can be connected in any other convenient way.

The tie-rope, or the like, connects the two 50 "falls," or suspending tackles, both when engaged with the hooks and when released therefrom which not only keeps the hooks securely engaged with the links when the

boat is suspended, but on release at once clears the occupants of the boat of everything attached to the davit falls and, when 55 the boat is to be attached, as soon as one fall is laid hold of, also brings the other "under control."

Although I have mentioned the lever-hook as being employed at one end only, such an 60 arrangement may, if desired, be used at both ends in which case the boat may be released from either end.

Figure 2 shows a modification in which lever-hooks are thus employed at each end 65 of the boat. The parts at both ends are marked with letters of reference the same as those used to denote like parts of the lever-hook and connections shown at the stern of the boat in Figure 1 and require no 70 further description.

What I claim is:—

1. A suspending and releasing device comprising two supports at least one of which has a pivoted lever hook, suspension elements 75 engaging said supports, means for moving said pivoted lever hook to shift the hook engaging suspension element across the axis of said hook to displace the strain of suspension from one to the other side thereof, 80 and tie-means connecting said suspension elements, and serving, under the strain of suspension, to urge the hook open or closed substantially as described.

2. A suspending and releasing device having two supports, at least one of which comprises a hook having a pivoted member, suspending elements adapted to engage said supports, that which engages the hook lying in suspending position to one side of the 90 axis of the pivoted member, tie-means extending between said suspending elements and serving to hold the latter in suspending position, together with means to swing the pivoted member on its axis to free the suspending element from the hook engaged thereby. 95

In testimony whereof I have signed my name to this specification in the presence of two subscribing witnesses.

AUGUSTUS WILLIAM LOUIS SCHERMULY.
